CIGAR-LIGHTER

Joseph H. Cohen, Bridgeport, Conn.

Original application October 4, 1926, Serial No. 139,354. Divided and this application June 7, 1928. Serial No. 283,628

8 Claims. (Cl. 219—32)

This invention relates to cigar-lighters, and more particularly to igniting units for cigar-lighters adapted for use with commercial currents. This application is a division of my co-pending application, Serial No. 139,354, filed October 4, 1926.

Heretofore, there have been many proposals of electric cigar-lighters intended for use with commercial currents of about 110 voltage, but these, for the most part, have failed to go into general use. Some involved the use of transformers, and hence were not universal to both alternating and direct currents; some had extra resistances in their bases which would heat-up and thus increase the fire hazard; some had heating or igniting elements of such size that an excessive amount of heat would be developed, making it uncomfortably hot for persons using the cigar-lighters; and some, by reason of their necessary sizes and forms, were unsuitable for use on a table or desk in an office or home.

Hence, an object of this invention is to provide an electric-lighter for commercial currents, which has none of the disadvantages above referred to, and yet which can be economically made, so that its cost to the customer will be relatively small.

This application embraces the heating or igniting unit which, according to the present invention, is so made that substantially all of the heat energy produced is confined to a zone limited in area to that of the mouth of an ordinary pipe bowl, and the said zone is inwardly removed and actually spaced from the sides of the holder, so that no appreciable amount of heat will reach the sides of the holder to heat the same. Hence, danger of the user burning his hands while grasping the holder in using the cigar-lighter is avoided. Moreover, the heating unit, according to this invention, is so arranged that no amount of heat is transferred to the holder by either convection or conduction while the cigar-lighter is being used.

Even though it has these structural and functional advantages, the heating unit of this invention is so arranged that it may be removed from and replaced in the holder as a unit with safety and without danger of the person performing the operation being shocked.

Other objects and advantages will hereinafter appear.

In the accompanying drawing, which shows the form of the invention as at present preferred—

Figure 1 is a plan view of the top of the igniting unit of the present invention.

Fig. 2 is a vertical section of the igniting unit shown in Fig. 1, showing part of the holder for the unit in dot-and-dash lines.

Fig. 3 is a side elevation of the igniting unit.

Fig. 4 is a perspective view of the disassembled parts of the heating or igniting unit, showing one part above the other in the order in which the parts are put together upon each other.

The igniting unit of the present invention is adapted to be removably supported in a suitable holding device and comprises a coil 10 of high resistance wire wound in helical form and laid in a spiral groove 11 formed in a disk 12 of porcelain or other fire-resisting or refractory material which reflects a substantial amount of heat developed in the coil 10 to the smoker's article to be ignited which is held directly above the device for the purpose. Beneath the disk 12 there is placed a disk 13 of mica or other heat-reflecting material whose function is to reflect any heat coming from the coil 10 or disk 12 up against the disk and thus retard the downward passage of heat developed in the coil 10. Directly beneath the mica disk 13 and supporting the same is a relatively thick cylindrical block 14 of asbestos wool or other heat-resisting and heat-insulating material. This block 14 prevents any heat which is reflected past or thru the mica disk 13 from passing downwardly into the holder for the igniting unit. The block of asbestos is backed by a plate 15 of porcelain which has a cup 16 to receive the lower end of the block. The bottom part of the backing plate 15 is reduced at 17 to substantially fit the lip of a holder 18, indicated in dot-and-dash lines, so that the flange 19 of the backing plate 15 rests on the supporting member 18.

The above described parts of the igniting unit are secured together to form a unitary structure, which may be placed in and taken out of a holder 18 as such, by screw-threaded rods 20, 21 and 22 having heads located in countersunk apertures in the disk 12 and drawing the parts together and holding them so by means of screw-threaded members 23, 24 and 25 respectively, the member 25 being an ordinary nut, while the members 23 and 24 constitute contacts, as hereinafter described.

Direct contact of the smoker's article with the coil 10 is prevented by a cover disk 26 of mica which covers the porcelain disk 12 and which has apertures 27 therein to permit the heat developed in the coil 10 to pass therethrough to the smoker's article. This mica disk 26 is securely held in place on the disk 12 by a ferrule 28 surrounding

the disk 12 and having a flange 29 overlying the cover disk 26. The ferrule 28 is secured to the disk 12 by spinning the lower edge of the ferrule over the lower edge of the disk 12.

5 It should be noted that the mica disk 26 covers the apertures in the disk 12 in which the screws 20, 21 and 22 are located, and that consequently the device cannot be tampered with without practically destroying it by the removal of the ferrule 28.

10 As thus constructed, the igniting unit may be inserted in a supporting member by placing the backing plate 15 on the upper edge of the holder 18. The igniting unit is secured in this position 15 by a guard 30 which bears down upon the flange 19 provided on the backing-plate 15 and which is indicated in dot-and-dash lines in Fig. 2.

15 In order that the heat generated by the coil 10 may be drawn by suction therethrough and 20 by a natural draft, the present invention provides perforations 31 in the disk 12 and spaces the bottom of the disk 12 from the mica disk 13 by legs 32 formed on the disk 12. In addition, the igniting unit is spaced inwardly from the guard 25 30 so as to allow air to follow the paths of the arrows shown in Fig. 2, that is, down between the guard 30 and the igniting unit, then under the disk 12 through the spaces provided by the legs 32, then up through the perforations 31 in 30 the disk 12, past the coil 10 where it is heated, and out thru the apertures 27 in the mica cover disk 26 to the smoker's article.

35 In order that current may be carried to the coil 10, the inner end of the coil is placed under the head of the screw 21 which, at its lower end, is provided with the contact member 24; and the outer end of the coil is placed under the head of the screw 20 which at its lower end is provided with the contact member 23 which is 40 slit so as to frictionally engage the sides of a socket in which it may be placed.

45 Variations and modifications may be made within the scope of this invention and portions of the improvements may be used without others.

Having thus described the invention, what is 50 claimed as new and for which it is desired to obtain Letters-Patent, is:—

1. A heating unit for electric cigar-lighters for house currents, comprising a coil of resistance 55 wire; a porcelain disk in which said wire is mounted; a mica disk located directly beneath said porcelain disk and adapted to reflect heat generated by said coil upwardly toward said porcelain disk; a relatively thick block of loose 60 asbestos wool for supporting said mica disk and porcelain disk, said loose asbestos wool being adapted to prevent the passage through it of heat generated in the coil and passing through the mica disk; and a base member of rigid material for supporting said block of loose asbestos wool.

2. A heating unit for electric cigar-lighters for house currents, comprising a coil of resistance 65 wire; a porcelain disk in which said wire is mounted, said porcelain disk being provided with apertures through which air is drawn by suction when a smoker's article is being lighted; a mica disk spaced from said porcelain disk, located directly beneath the said disk and adapted to reflect heat generated by said coil and passing through said apertures in said porcelain disk toward said disk; a relatively thick block of loose asbestos wool supporting said mica disk and porcelain disk, said loose asbestos wool being adapted to prevent the passage through it of heat gen-

erated in said coil and passing through said apertures and said mica disk; and a base member of rigid material for supporting said bed of asbestos wool.

3. A heating unit for electric cigar-lighters for 80 house currents, comprising a coil of resistance wire; a porcelain disk in which said wire is mounted, said porcelain disk being provided with apertures through which air is drawn by suction when a smoker's article is being lighted; a mica disk spaced from said porcelain disk, located directly beneath the said disk and adapted to reflect heat generated by said coil and passing through said apertures in said porcelain disk toward said disk; a relatively thick block of loose asbestos wool supporting said mica disk and porcelain disk, said loose asbestos wool being adapted to prevent the passage through it of heat generated in said coil and passing through said apertures and said mica disk; and a rigid base member 85 having a cupped-portion for receiving and supporting said block of asbestos wool.

4. A heating unit for electric cigar-lighters for 90 house currents, comprising a resistance element; a resistance element holder of high proof refractory material; a heat reflecting member located beneath the said resistance element holder; an insulator supporting said heat reflecting member and resistance element holder, said insulator being non-conductive of heat; a base member for 95 supporting said insulator; and bolts passing through the resistance holder, heat reflecting member, insulator, and base member adapted to hold the same together as a unit.

5. A heating unit for electric cigar-lighters for 100 house currents, comprising a resistance element; a resistance element holder of high proof refractory material; a heat reflecting member located beneath the said resistance element holder; an insulator supporting said heat reflecting member and resistance element holder, said insulator being non-conductive of heat; a base member for 105 supporting said insulator; and bolts passing through the resistance holder, heat reflecting member, insulator, and base member adapted to hold the same together as a unit, at least one of said bolts being electrically connected with one 110 end of the resistance elements and having at its lower end a switch-contact lug.

6. A heating unit for electric cigar-lighters for 115 house currents, comprising a resistance element; a resistance element holder of high proof refractory material; an insulator supporting said resistance element holder, said insulator being non-conductive of heat; a base member for supporting 120 said insulator; and bolts passing through the resistance holder, insulator, and base member adapted to hold the same together as a unit, at least one of said bolts being electrically connected with one 125 end of the resistance elements and having at its lower end a switch-contact lug.

7. A heating unit for cigar-lighters, comprising a base member having a cupped portion; an intermediate member non-conductive of heat fitting in the cupped portion of the base member 130 and supported thereby; a resistance element; and a resistance element holder having legs supported by the intermediate member and spacing the body portion of the resistance element holder from the intermediate member to provide an air 135 gap therebetween, said base member having a circumferential shoulder adapted to engage a housing in which the unit is supported.

8. A heating unit for cigar-lighters, comprising a base member having a cupped portion; an 140

intermediate member non-conductive of heat fitting in the cupped portion of the base member and supported thereby; a resistance element; and a resistance element holder having legs supported by the intermediate member and spacing the body portion of the resistance element holder from the intermediate member to provide an air gap therebetween, said base member having a circumferential shoulder adapted to engage a housing in which the unit is supported, and another circumferential shoulder adapted to be engaged by a ring attachable to the housing to hold the base member on the housing with the first-named shoulder in firm engagement with the housing. 80
